US00D655279S

(12) **United States Design Patent**
Buzzard et al.

(10) **Patent No.:** **US D655,279 S**
(45) **Date of Patent:** **** Mar. 6, 2012**

(54) **VIDEO UNIT WITH INTEGRATED FEATURES**

(75) Inventors: **Kyle A. Buzzard**, San Jose, CA (US);
Andrew R. Church, Oakland, CA (US);
Ashok T. Desai, Fremont, CA (US);
Daniel K. Harden, Palo Alto, CA (US);

(57) **CLAIM**

The ornamental design for a video unit with integrated features, as shown and described.

DESCRIPTION

FIG. 1 is a top perspective view showing a video unit with integrated features design according to another embodiment; FIG. 2 is a front view of the video unit with integrated features design of FIG. 1; FIG. 3 is a back view of the video unit with integrated features design of FIG. 1; FIG. 4 is a side view of the video unit with integrated features design of FIG. 1; FIG. 5 is another side view of the video unit with integrated features design of FIG. 1; FIG. 6 is a top view of the video unit with integrated features design of FIG. 1; and, FIG. 7 is a bottom view of the video unit with integrated features design of FIG. 1. The broken lines of the preceding FIGURES illustrate a boundary and, further, the broken lines are for illustration only and form no part of the claimed design.
